(57) **CLAIM**

The ornamental design for a motorcycle cover, as shown and described.

DESCRIPTION

FIG. 1: Top right perspective view;

FIG. 2: Bottom plan view;

FIG. 3: Side elevation (both side views are identical);

FIG. 4: Front elevation; and,

FIG. 5: Rear elevation.

The broken lines in the drawing FIGS. 1 and 2 represent stitching and are considered part of the claimed design.
